UNITED STATES PATENT OFFICE.

JAMES ADAIR, OF NEW YORK, N. Y.

SHIRT.

SPECIFICATION forming part of Letters Patent No. 407,765, dated July 30, 1889.

Application filed May 18, 1889. Serial No. 311,326. (No model.)

To all whom it may concern:

Be it known that I, JAMES ADAIR, a citizen of the United States, and a resident of New York, in the county and State of New York, 5 have invented a certain new and useful Improvement in Shirts, of which the following is a specification.

My invention relates to that class of articles designated as "shirts," and has for its object 10 the provision of a device simple in construction, cheap in manufacture, and which will be efficient in practical use.

To attain the desired end, my invention 15 consists in the construction and arrangement of parts hereinafter described, and pointed out in the claim.

In the drawings which form a part of this 20 specification, Figures 1 and 2 are perspective views of different positions of an article constructed according to my invention; and Fig. 25 3 is a transverse section through the bosom of the same, showing the fly secured thereto.

Like letters of reference wherever they occur indicate corresponding parts in all the figures.

Referring again to the drawings, A and A' 30 represent the two parts of the open bosom of my shirt, which is preferably of the closed-back type of construction. To the underlying part A of the bosom I attach an independent fly B, extending the full length of the bosom and entirely loose therefrom, except at the points b, at the top and bottom of the bosom, a short distance from the edge of the 35 bosom, and at one or more intermediate points a², at which places the fly B and bosom A are connected by tacks or stitches, as is clearly shown in the drawings.

The upper part A' of the bosom of my shirt, 40 which normally overlaps the part A and fly B, is provided with one or more button-holes a', which may be secured to corresponding underlying button-holes b' in the fly B, by means of studs or equivalent fastening devices.

When my improved shirt is laundered, the 45 fly B and the bosom A are securely held together by the starch therein contained.

In practical operation, after the shirt is put on the studs are first inserted in the button-holes of the overlapping part A' of the bosom, 50 and the portions of the edge b² of the fly B adjacent to the button-holes b' lifted up and detached from the bosom A, whereupon the studs may be easily inserted in and engaged with the said button-holes b', the undisturbed 55 portions of the fly B remaining rigidly secured to and cemented upon the bosom by the starch, as stated above.

My shirt may be very rapidly and economically manufactured, and my improvement 60 may be applied to "stock" shirts, or shirts that are in use. My improved shirt may also be very readily washed and ironed. It is handsome in appearance, and is convenient 65 in use, as the studs are so easily engaged with and removed from the same.

As it is evident that many slight changes 70 in the construction and relative arrangement of parts might be resorted to without departing from the spirit and scope of my invention, I would have it understood that I do not 75 restrict myself to the particular construction and arrangement of parts shown and described, but that I reserve the right to make such changes; and that

What I claim, and desire to secure by Letters Patent, is—

The combination, with the part A of the shirt-bosom, the tacks b, placed at the top and bottom of the same a short distance from the 80 edge thereof, the intermediate tacks a², and with the independent fly B secured to the bosom A by the tacks b a², of the part A' of the bosom adapted and arranged to overlap the bosom A and the fly B, substantially as 85 described.

In testimony of the foregoing specification I do hereby sign the same, in the city of New York, county and State of New York, this 15th day of May, A. D. 1889.

JAMES ADAIR.
